UNITED STATES PATENT OFFICE

MERRILL G. BENJAMIN, OF LAKEWOOD, OHIO

COMBUSTION CONTROL

Application filed October 4, 1929. Serial No. 397,433.

My invention pertains to systems for controlling combustion and, in particular, to systems of the type mentioned which are applicable to the furnaces of a steam-boiler plant.

The principal object of my invention is the provision of a combustion-control system that shall be entirely automatic in its operation.

Another object of my invention is to provide a control system which shall be responsive to the steam pressure in a boiler or in the output main connecting a plurality of boilers, if such is provided, and shall operate to maintain a constant predetermined pressure therein.

Another object of my invention is to provide a control system in which a variation in steam pressure causes the operation of means, such as boiler and furnace auxiliaries, to restore the steam pressure to its normal value, the speed of the various auxiliary-controlling means being made proportional to the magnitude of the variation of the steam pressure from normal.

Another object of my invention is to provide means for decelerating the adjustment of the boiler and furnace auxiliaries when the steam pressure tends to return to normal.

Another object of my invention is to provide indicating means at a central point for indicating the adjustment of a plurality of boiler and furnace auxiliaries.

Another object of my invention is to provide means for supplementally controlling the adjustment of the various auxiliaries in accordance with certain functions of the boiler and furnace which will be described in more detail hereinafter.

A still further object of my invention is to utilize the characteristics of a turbo-generator unit for driving one of the auxiliaries of a boiler furnace as well as a generator for supplying current to motors driving other auxiliaries thereof.

I am aware that it has previously been proposed to control the forced draft supplied to a boiler furnace by varying the position of an inlet damper or by varying the speed of a forced-draft fan in accordance

with the boiler steam pressure and that the control of the induced draft by similar means has also been suggested. I understand, also, that it has previously been the practice to control the rate of fuel feed to a furnace by varying the speed of a motor-driven stoker by the same function of the boiler. I propose, however, to make use of these fundamental principles in a new combination which shall function to accomplish the objects above set forth.

The present invention is related to that described and claimed in my copending application Serial No. 323,145.

In accordance with the system of my invention, I provide a motor-driven, forced-draft fan and a turbine-driven induced-draft fan, as well as a motor-driven stoker or equivalent fuel-feeding means. The turbine for driving the induced-draft fan serves also to drive a direct-current generator which is utilized as a source of energy for the motors driving the forced-draft fan and stoker or other fuel feeder. As the induced-draft fan requires a greater amount of energy than any other auxiliary, I propose to drive this unit by a turbine and make use of the same instrumentality to provide direct current for the other auxiliaries. The advantage resulting from this method of operating, obviously, is that direct-current control for auxiliary motors is much simpler than that for alternating-current motors. It is possible, furthermore, by regulating the speed of the turbo-generator, to control the speed of the other auxiliaries so as to provide an improved method of control. By varying the speed of these auxiliaries properly, it is possible, of course, to control the rate of combustion in a boiler furnace. As the system of my invention will generally be applied to a battery of boilers, such as is usually installed in a steam-electric generating plant, my invention contemplates the duplication of the control apparatus to be hereinafter described for one boiler, for each of the boilers in the battery.

As a means for controlling the speed of the boiler and furnace auxiliaries, I have disclosed the rheostatic control of the shunt field-magnet windings of the motors driving

certain of the auxiliaries and the usual valve control of the turbine driving the induced-draft fan, although it is obvious that any other known method of speed control for electric motors or other driving means may be employed.

For the primary control of the speed of the means for driving the auxiliaries, I employ a steam-pressure regulator which operates to 10 vary the speed of the auxiliaries, in inverse proportion to the pressure of the steam in the boiler or steam header, to vary the rate of combustion in a similar ratio. In addition to the primary control by means of the 15 steam pressure, my system includes additional supplemental controlling means for the various auxiliaries, independent of the steam-pressure regulator and of each other, for independently controlling the speed of 20 any auxiliary of any furnace. These supplemental control means are responsive to certain boiler and furnace conditions which will be described in detail later.

For a more complete description of the 25 system of my invention, reference should be had to the following specification and the accompanying drawings, in which

Figure 1 illustrates, diagrammatically, one of a plurality of boilers, together with the 30 control equipment for the forced-draft and induced-draft fan motors thereof and the indicators therefor, and

Fig. 2 illustrates the control equipment for the stoker motor of the boiler shown in Fig. 1 35 and the master steam-pressure regulator, as well as a second boiler, which is adapted to have similar control equipment associated with it.

Referring now in detail to both figures of 40 the drawings, furnaces 10 and 11 are adapted to generate steam in boilers 12 and 13 for supplying any type of load, a turbine (not shown), for example, connected to the steam header 14.

The furnace 10 is provided with a motor-driven fuel feeder 15 which may be a stoker or a feeder for pulverized coal, and also with a forced-draft fan 16 and an induced-draft fan 17. The furnace 11 is provided with 50 similar auxiliaries, namely, a stoker 18, forced-draft fan 19 and induced-draft fan 20. Electric motors 21 and 23 are provided for driving the forced-draft fan, the stoker of the furnace 10 and similar motors 24 and 26 are 55 arranged to drive similar auxiliaries of the furnace 11. The motors may be coupled to the auxiliaries by any known driving means, but I have illustrated the auxiliaries directly connected to the shafts of the motors. For 60 driving the induced-draft fan 17 I provide a steam turbine 22 which is adapted to be supplied with steam from the header 14 under the control of a regulating valve 28.

In addition to driving the induced-draft fan, the turbine 22 drives also a direct-current

generator 25 which is of the compound-wound type and is adapted to supply current to the direct-current compound-wound motors 21 and 23 which drive the forced-draft fan 16 and the stoker 15, respectively. 70

From this point on, the description of my invention will refer only to the auxiliaries of the furnace 10, it being assumed that duplicate control equipment will be provided for the auxiliaries of the furnace 11. 75

The speeds of the auxiliary motors 21 and 23 which drive the forced-draft fan and the stoker of the furnace 10, are controlled by rheostats 27 and 29, although, as above stated, any equivalent speed-controlling means may be substituted. The speed of the turbine 22 is governed by the setting of the valve 28 controlling the admission of steam from the header 14 to the turbine, in a manner which 80 will be described more fully hereinafter. 85

As indicated at the beginning of this specification, it is the object of my invention to provide for the adjustment of the speeds of the auxiliary motors in accordance with the steam pressure and also in accordance with the variation in certain boiler and furnace conditions. The exact mechanism by which this variation is accomplished will now be described in detail. 90

Connected to the steam header 14 is a Bourdon tube 30 (Fig. 2) or other equivalent means responsive to the steam pressure in the header. The master steam-pressure regulator, indicated generally at 31, is adapted to be controlled by the Bourdon tube. This regulator comprises a shaft 32 on which is loosely journaled a pivoted contact arm 33, the end of which is connected to the end of the Bourdon tube by means of a link 34. 95

A contact-bearing disc 35 is also mounted on the shaft 32 and is provided with teeth on its periphery for engagement with a worm 36. A contact arm 37 is mounted on the shaft 32 and is adapted to be frictionally engaged by the disc 35 and rotated therewith until it 100 engages either one of the fixed contacts 38, 39. 105

The worm-wheel disc 35 is provided with two conducting segments 40 and 41, separated by an insulating spacer, which are adapted to be engaged by the contact arm 33 when the latter is moved in either direction from the central or neutral position in which it is illustrated. 110

The contact arm 33, under the influence of the Bourdon tube 30, is adapted to control the operation of a motor 42 having forward and reverse field windings 43 and 44. The motor 42 will be referred to hereinafter as the indicator-generator motor because it is directly connected to the rotor of a synchronous, poly-phase, alternating-current machine 45 which serves to supply current to other electrical devices, as will be explained more fully in the course of the following description. It may be noted, however, at this point, that the 115 120 125 130

stator of the machine 45 is adapted to be energized from any convenient source. The rotor is connected to a set of main conductors such as 46 which constitutes an indicator bus.

Connected to the shaft of the motor 42 is a pair of contact arms 48 and 49 which engage resistors 50 and 51. These resistors have their corresponding terminals connected to current sources of opposite polarity and thus constitute a so-called potentiometer bridge. It will be obvious that, when the arms 48 and 49 take up the neutral position in which they are illustrated, the voltage difference therebetween will be zero and that, as the arms move simultaneously in the one or the other direction from the neutral position, a constantly increasing voltage of the one or the other polarity will exist thereacross.

The voltage across the arms 48 and 49 is applied to the armature of a motor 52 having a shunt field winding 53. The motor 52 is mechanically connected to the rotor of an alternating-current machine 54, similar in all respects to that shown at 45, which will be referred to as the control generator, since it supplies current to the conductor 56 which constitutes a control bus.

It may be desirable to employ a speed-reduction gear between the motors 42 and 52 and the generators 45 and 54, since the latter are designed only for a relatively limited rotative movement.

Referring again to the contact arm 37, this member is adapted to complete a circuit for a relay 57 when it engages either of its associated fixed contacts 38, 39. The relay 57, when energized, operates to shunt a resistor 58 in the circuit of the field winding 53 of the motor 52, in order to decrease the speed of the latter in accordance with certain conditions to be described later. The relay circuit is completed through the arm 37, one or the other of contacts 38 and 39, one or the other of a pair of contact segments 38' and 39' connected thereto respectively, and mounted on the disc 35, and a fixed contact roller 37 adapted to engage either of the segments 38' and 39', depending on the position of the disc 35. Whenever the latter is out of its neutral position, only one of the segments is engaged by the roller, the other remaining ineffective. The purpose of this construction will appear subsequently.

Having described the master steam regulator, I shall now proceed to explain the operation of the control apparatus for the stoker motor 23.

The shaft of the motor 23, in addition to being connected to the stoker 15, has an extension to the operating arm of the speed-controlling rheostat 29. The connection between the motor shaft and the rheostat arm, however, is not permanent but is adapted to be effected, when desired, by means of a magnetic clutch, indicated at 60, which is of stand-

ard design and is adapted to be controlled by solenoids 61 and 62. When one of said solenoids is energized, the clutch 60 so connects the rheostat arm to the shaft of the motor 23 that it is rotated in one direction. Energization of the other solenoid of the clutch will cause rotation of the rheostat arm in the reverse direction. It will be obvious, therefore, that the setting of the rheostat 29 and, consequently, the speed of the motor 23, may be varied at will by the successive energization of the solenoids 61 and 62 of the clutch 60. Instead of the magnetic clutch I may employ a separate reversible motor for operating the rheostat 29.

For controlling the solenoids of the clutch 60, I provide a contact-making mechanism indicated generally at 63. This mechanism includes a disc 64 provided with two conducting segments 65 and 66, insulated from each other, which are adapted to be engaged by a contact arm 67 which is actuated in accordance with the movement of shaft 29' on which the contact arm of rheostat 29 is mounted. The disc 64 is mechanically coupled to the rotor of a polyphase, synchronous, alternating-current, machine 68 similar to those shown at 45 and 54, except that the machine 68 operates as a motor when supplied with current of suitable characteristics from the control generator 54.

The generator 54 and the motor 68, being supplied with alternating current from the same source, tend to maintain their rotors stationary in corresponding positions. This synchronizing action is well known and has been employed heretofore where it was desired to move one element in synchronism with another. The theory underlying this operation is known, and therefore, needs no explanation here. It is sufficient to explain that any movement of the rotor of the generator 54 will immediately be communicated to the rotor of the motor 68 and, therefore, to the contact disc 64. The positions of the disc 64 and the contact arm 67 on their respective driving shafts may be reversed if desired.

The motor 68, however, differs from the generator 54 in that the stator winding of the motor 68 is adapted to be rotated by means of a worm 69, the motor housing being supported for rotation and provided at its periphery with teeth for engagement by said worm.

It will be obvious, of course, that the position of the rotor of the motor 68 is controlled not only by the position of the rotor of the generator 54 but also by the position of the stator of the motor 68. That is to say, the rotor of the motor 68 may be shifted as a result of a shift in the position of the rotor of the generator 54 or a shift in the position of the stator 68.

The worm 69 is adapted to be rotated by the movement of the shaft 29' which carries

the contact arm of the rheostat 29. The connection of the worm 69 to the shaft 29', however, is not permanent but is effected only when the solenoid 70 of a magnetic clutch 71 is energized. A manual switch 72 is provided for controlling the energization of the solenoid 70 in series with either of the solenoids 61 and 62 of the clutch 60 and, in addition, a balanced relay 73 is also effective to control said solenoids.

The relay 73 comprises a pivoted beam adapted to be actuated by a plurality of magnet coils 74, 75, and 76. The coil 74 is connected in circuit with a rheostat 77, the contact arm of which is driven by the shaft 29'. The energization of the coil 74, therefore, varies directly with the speed of the stoker motor 23 which, as pointed out previously, responds directly to variations in the steam pressure in the header 14. The coil 75 is energized under the control of a steam-flow meter 78 which is so connected as to measure the steam output of the boiler 12. The coil 76, similarly, is energized under the control of a feed-water input flow meter 79 which measures the flow of feed water into the boiler 12. It will be understood that the feed water is supplied to the boiler from the usual feed-water heater by means of a pump, not shown, through the pipe 80.

The steam-flow meter 78 and the feed-water flow meter 79 are standard devices and are, therefore, not described in detail.

An indicating panel 81 may be provided with a plurality of indicators for communicating to the operators of the station a knowledge of the adjustment of the various auxiliaries. One of these indicators 82, is provided with two pointers, one of which is actuated by the indicator motor 84 connected to the indicator bus 46, the other being actuated by the indicator motor 83 connected to the control bus 56.

The motor 83 moves in synchronism with the generator 45, and the motor 84, similarly, moves in synchronism with the generator 54. The two pointers on the dial 82, therefore, acquaint the station operators with the actual steam pressure in the header and the adjustment of the speeds of the various auxiliaries to restore the pressure to normal.

The indicator 85 is driven by the indicator motor 86 which is connected to the rotor of an indicator generator 87 mounted on the shaft 29'. The indicator 85, therefore, always shows the position of the rheostat 29 which controls the speed of the stoker motor 23.

Having described the master control regulator and the control apparatus for the stoker motor in detail, I shall now explain the method of operation of my system. In this description, it will be assumed first that the steam pressure in the header 14 is at its normal value, that the steam-pressure regulator 31 and all of its elements are in their

neutral positions, that the motors 42 and 52 are stationary and that the stoker motor 23 is rotating at normal speed, at which sufficient fuel is supplied to the grate to maintain normal boiler pressure for normal demand on the station. It will also be assumed that the contact member of the relay 73 is in the neutral position, as well as the switch 72 and the contact 67.

If the boiler pressure falls below its normal value, as a result of an increase in the station load, for example, the Bourdon tube 30 will contract and, through the link 34, will cause the contact arm 33 of the pressure regulator 31 to engage the segment 41. This results in the completion of a circuit through the forward field winding 43 and armature of the motor 42 which thereupon begins to rotate. As the motor 42 rotates, it shifts the position of the rotor of the indicator generator 45, shifts the arms 48 and 49 of resistors 50 and 51 away from the neutral position and, at the same time, tends to restore the disc 35 to a position in which the arm 33 engages the insulating spacer between the conducting segments 40 and 41. When this restoration has been accomplished, further rotation of the motor 42 is stopped. The shifting of the rotor of the generator 45 causes a corresponding shift in the position of the pointer actuated by the motor 83 on the control panel.

The motor 52, being subject to the difference in voltage across the arms 48 and 49, continues to turn the rotor of the control generator 54. The rotor of the generator 54 causes a corresponding shift in the position of the rotor of the motor 68 which thereupon moves the disc 64 so that the contact arm 67 engages one of the conducting segments 65, 66. A circuit is thereby completed for one of the solenoids 61, 62 of the magnetic clutch 60 to cause a movement of the shaft 29' in such direction that the rheostat 29 will be adjusted to increase the speed of the stoker motor 23 so that the rate of combustion in the furnace 10 will likewise be increased and the boiler pressure restored to normal.

As the adjustment of the rheostat 29 proceeds, the contact arm 67 is returned to its neutral position between the segments 65 and 66 and further adjustment of the stoker motor rheostat is stopped. The movement of the rheostat arm 29 is indicated on the board 81 by means of the indicator motor 86 and the indicator 85.

The control-generator motor 52 continues to shift the position of the rotor of the control generator 54 until the steam pressure in the header 14 begins to increase to its normal value. When this result occurs, the contact arm 33 of the master regulator 31 engages the contact segment 40 to cause a reverse rotation of the motor 42 and a decrease in the speed of the motor 52.

- If the restoration of the steam pressure proceeds at a rapid rate, the contact arm 37 will engage the fixed contact 38 to energize the relay 57 which short-circuits the resistor 58 in the circuit of the shunt field winding 53 of the motor 52 to further decrease the speed of the latter. If the restoration of the steam pressure proceeds at a comparatively slow rate, however, the speed of the motor 52 is decreased only by the return of the rheostat arms 48, 49 to the neutral position. In any case, the speed of the motor 52 is dependent upon the difference between the actual header pressure and normal pressure.
- Upon the occurrence of a sudden change in steam pressure, it is desired that adjustment of the auxiliaries proceed at maximum speed. The construction of the contact arm 37, the segments 38' and 39', and the roller 37', in connection with the contacts 38 and 39, insures that, under such conditions, the speed-reducing effect of the operation of the relay will be prevented until the restoration of normal conditions has actually proceeded to a substantial extent.
- The reverse rotation of the motor 52 causes an adjustment of the stoker-motor rheostat 29 in the reverse direction to reduce the motor speed to normal.
- In the preceding description of operation, no mention has been made of the relay 73. This relay, however, performs an important function. It operates to control the speed of the stoker motor supplementally so that the motor speed will be further adjusted in accordance with conditions in the boiler.
- If the quality of the fuel supplied to the stoker 15 varies, for example, the actual amount of combustible fuel supplied to the grate will likewise vary. If coal of a lower grade is placed in the stoker hopper, less heat will be supplied by the furnace to the boiler and less steam generated thereby. The steam output of the boiler will thereby be decreased and this decrease will be registered by a change in the energization of the coil 75 which is controlled by the steam-flow meter 78. This change in the energization of the coil 75 of the relay 73 will cause the pivoted beam of said relay to move so that its contact arm will engage one of the fixed contacts to energize the coil 70 of the clutch 71 in series with one of the coils 61, 62 or of the clutch 60.
- The energization of the coils 61, 62 will cause an adjustment of the stoker-motor rheostat 29, as explained heretofore. The simultaneous energization of the coil 70 will cause a shift in the position of the stator of the motor 68 which has the effect of further adjusting the position of the stoker-motor rheostat through the contact mechanism 64 to 67. It will thus be apparent that a change in the grade of the fuel supplied to the furnace will cause a change in the stoker-motor speed so that more or less coal will be supplied per unit of time to compensate for the decrease in the percentage of combustible matter in the coal and to maintain a constant supply of combustible matter per unit of time for any given setting of the master regulator.
- A similar result is effected by a change in the rate of feed-water supply. Ordinarily, feed water is supplied at a definite rate and at a definite temperature. If anything happens to vary the rate of feed water supply, for example, the failure of the feed-water pumps (not shown), the energization of the coil 76 of the relay 73 will be so changed by the operation of the feed-water flow meter 79 as to adjust the setting of the stoker-motor rheostat 29, in the manner described above, to decrease the amount of coal supplied to the furnace.
- It will be apparent that the supplemental control of the stoker motor automatically regulates the supply of fuel to the furnace in accordance with the amount of heat absorbed by the boiler. The heat absorption of the boiler is measured by the difference between the heat in the steam output and that in the feed-water input. The relay 73 may readily be calibrated to effect any desired control in accordance with the characteristics of the boiler operation. The amount of fuel supplied to the furnace, in other words, is varied in accordance with the amount of heat absorbed by the boiler.
- The manual switch 72 may be employed to effect the control of the stoker-motor rheostat in the same manner as that described heretofore in connection with the relay 73, the contacts of the switch 72 being in parallel with those of the relay 73. The switch 72 may preferably be mounted on the control panel 81 instead of in the position shown.
- The control of the forced-draft fan motor 21 is effected in a manner similar to that described above for the stoker motor 23, the only difference being in the functions of the boiler and furnace to which the supplemental control for these auxiliaries is responsive.
- The speed of the forced-draft fan motor 21 is adjusted in response to the movements of the master steam-pressure regulator 31 in identically the same manner as the speed of the stoker motor. The supplemental control of the speed of the forced-draft motor is, however, effected by a balanced relay 87 which comprises a pivoted beam and solenoids 88, 88' and 89 for actuating a contact arm mounted on the beam into engagement with one of two fixed contacts 90. The solenoid 88 is energized in accordance with the power input to the forced-draft fan motor 21, being connected to a shunt 91 in the motor circuit or other equivalent power-measuring device. The solenoid 89 is energized in accordance with the operation of an air-pres-

sure regulator 92 which is similar to the steam-flow meter 78 in that it produces an electric current proportional to the air pressure in the duct between the fan 16 and the ashpit of the furnace 10. The solenoid 88' is controlled by a rheostat 89' actuated by the same means employed for the control of the rheostat 27 of the forced-draft fan motor 21.

10 The supplemental control of the forced-draft fan motor, therefore, may be said to be responsive to the difference between the power input to the fan motor and the forced-draft air pressure.

15 By employing these functions, it is possible, by proper calibration of the relay 87, to maintain a constant rate of air supply to the furnace, that is to say, the weight of air supplied per minute is maintained constant, at the rate fixed by the position of the master regulator, for all conditions of boiler load.

20 The speed control of the turbine 22 which drives the induced-draft fan 17 and the generator 25 is effected by the master steam pressure regulator through a combination of self synchronous motors, electromagnetic clutches and mechanical connections therebetween, in the form of shafts and gearing, in the same manner as that described for the 25 control of the speed of the stoker motor 23, except that the controlling unit is the valve 28 which governs the admission of steam from the header 14 to the turbine 22 instead of a rheostat, such as that shown at 29, for controlling the speed of the motor 23 through 30 changes in the excitation of its shunt field-magnet winding.

35 The supplemental control of the turbine 22 which drives induced-draft fan is effected by a furnace-pressure regulator 93. This device comprises a bell float which is affected by the pressure of the gases in the combustion chamber of the furnace 10, to increase the speed of the turbine 22 by the same means described in connection with the stoker motor, when the furnace pressure tends to increase. The furnace pressure, therefore, is maintained at substantially a constant value, since an increase therein tends to increase the speed 40 of the turbine 22 and the induced-draft fan which tends to decrease the furnace pressure.

45 It will be understood, of course, that, if the header pressure increases above normal, a corresponding adjustment of all the boiler and furnace auxiliaries will be effected to decrease the rate of combustion.

50 The positions of the rheostat 27 and the valve 28 which control the speeds of the forced-draft fan motor 21 and the turbine 22 may be indicated on the control panel 81 by the indicators 94 and 95 which are driven by the indicator motors 96 and 97. These motors are actuated, respectively, by the indicator generators 98 and 99 which are me-

chanically coupled to the rheostat 27 and the valve 28.

55 As previously stated, the control equipment illustrated and described for the auxiliaries of the furnace 10 are to be duplicated for the auxiliaries of the furnace 11. It is to be understood that all auxiliaries of all boilers are simultaneously controlled by the master pressure regulator 31 and that the speed of any auxiliary of any boiler may be 60 independently controlled by its individual supplemental control equipment. This arrangement obviates the inflexibility of the systems of the prior art in which all auxiliaries are actuated in response to steam pressure and, at the same time, retains the advantage of a simultaneous primary control of all auxiliaries, still permitting individual adjustment of any auxiliary.

65 An additional advantage of the system 65 shown and described herein is that the use of a variable speed compound-wound generator in connection with variable speed compound-wound motors makes possible the design of the various units of the system in such manner as to take advantage of the inherent characteristics of this type of machines for the purpose of accurately controlling the operation of boiler and furnace auxiliaries.

70 A further advantage of the system of my invention is the fact that it is possible to utilize the generator 25, which is normally driven by the turbine 22, as a motor to drive the fan 17 in case of failure of the turbine, from a separate source of direct current. It is also 75 possible to provide means for connecting the motors driving the other auxiliaries to substitute sources of current so that their operation will not be suspended because of a failure of the turbine or the generator. A possible further modification would be to connect the generators of all the boilers corresponding to that shown at 22 for the boiler 25, in parallel, so that failure of the turbine 80 of one boiler would not prevent operation of the other auxiliaries thereof.

85 Although I have shown and described only a single embodiment of the system of my invention, it is not my intention to be limited thereto since my invention is susceptible of various changes and modifications.

90 It is to be particularly understood that the application of the system is not limited to installations of two boilers but may be extended to control automatically almost any number of boilers and furnaces. As already stated, the scope of my invention is not to be limited by any of the details of the showing and description but only by the terms of the appended claims.

95 I claim as my invention:

1. A control system for a plurality of boiler and furnace auxiliaries including forced-draft fans and stokers comprising a master steam regulator responsive to the

pressure in said boiler, for directly controlling the speeds of said auxiliaries, an induced-draft fan, a turbine for driving said fan, means actuated by the master regulator for controlling the admission of steam from the boiler to said turbine, motors for driving said auxiliaries and a generator driven by said turbine for supplying electrical energy to said motors.

10 2. The combination with a plurality of boilers and furnaces having auxiliaries for supplying elements of combustion to the furnaces, a master steam-pressure regulator for directly controlling the speeds of the auxiliaries, a turbine, an induced-draft fan driven thereby, means actuated by said regulator for controlling the admission of steam from said boiler to said turbine, motors for driving said auxiliaries and a generator driven by said turbine for driving said motors.

15 3. An automatic steam-generating station comprising a plurality of furnaces and boilers adapted to supply steam to a common load, individual fans and stokers for supplying elements of combustion to each of said furnaces, a master steam-pressure regulator directly controlling said fans and stokers for said boilers, a turbine for each of said boilers, means responsive to said regulator for controlling the admission of steam to said turbines, induced-draft fans driven by said turbines, motors for driving said first-mentioned fans and stokers and generators also driven by said turbines for supplying energy to said 35 motors.

40 4. A system of automatic combustion control for a boiler and furnace including a master regulator responsive to steam pressure, a forced-draft fan and a stoker directly controlled by said regulator for supplying elements of combustion to said furnace, an induced-draft fan for withdrawing the products of combustion from said furnace, a turbine controlled by said master regulator for driving said fan, motors for driving said forced-draft fan and stoker, and a generator driven by said turbine for driving said motors.

45 5. In a system for steam generation, a boiler and furnace, auxiliaries individual thereto for supplying elements of combustion and removing products thereof, including forced and induced-draft fans and a fuel feeder, a turbine for driving said induced-draft fan, a generator driven by said turbine and motors driven by said generator for operating said forced-draft fan and fuel feeder, and a master steam pressure regulator for controlling the turbine, forced-draft fan 55 and fuel feeder directly and the two latter indirectly through the former.

60 6. The combination with a plurality of boilers and furnaces adapted to supply steam to a common load, auxiliaries such as forced and induced-draft fans, a fuel-feeder and a

turbo-generator, individual to each of said boilers, said turbo-generator being mechanically connected to the induced-draft fan and electrically connected to said forced-draft fan and fuel feeder and means responsive to the steam pressure in said boilers for controlling the speed of said turbo-generator, whereby to adjust the rate of operation of said auxiliaries, and for simultaneously controlling individually the forced-draft fan and fuel feeder.

65 7. In a power system, a boiler and furnace having fuel and air-supplying means and means for withdrawing products of combustion, a generator for driving said fuel and air-supplying means, a turbine for driving said generator and said withdrawing means, and means responsive to the pressure of steam in said boiler for controlling the admission of steam to said turbine, and for simultaneously controlling individually the forced-draft fan and fuel feeder.

In testimony whereof I have hereunto set my hand:
